UNITED STATES PATENT OFFICE.

JOHN A. SECOR, OF NEW YORK, N. Y., ASSIGNOR TO THE GENERAL POWER COMPANY, OF NEW JERSEY.

DESIGN FOR A MOTOR BASE-FRAME.

SPECIFICATION forming part of Design No. 33,641, dated December 4, 1900.

Application filed September 8, 1900. Serial No. 29,435. Term of patent 14 years.

To all whom it may concern:

Be it known that I, JOHN A. SECOR, a citizen of the United States, residing in the borough of Brooklyn, in the city of New York, in the State of New York, have invented and produced a new and original Design for Motor Base-Frames, of which the following is a specification, reference being had to the accompanying drawings, making a part thereof.

Figure 1 is a perspective view of a motor base-frame, showing my new design. Fig. 2 is an end view, and Fig. 3 a plan or top view, further illustrating my said design.

As shown in the drawings, the leading or material feature of my design consists of a horizontal bottom portion A, the sides of which slope or flare outward, as shown more fully at *a b* in Fig. 1, with at one end thereof an upright frame portion B, which is transversely narrower at its top than at its bottom, with its lateral surfaces *c* flared or sloping outward toward the lateral edges of the bottom portion. Its back and front faces *e* are flat, or substantially so, and its lateral surfaces *c* rounded or curved, as shown more clearly in the top view, Fig. 3.

Rising from the bottom portion A the vertical journal-blocks C C have their front and back faces *fff* flat, or substantially so, while their tops being narrower than their lower parts their lateral surfaces flare or slope outward toward the edges of the bottom portion A, said journal-blocks C C being of a height less than that of the frame portion B, as shown in Figs. 1 and 2. This design is applicable to the base-frames of explosive-motors, steam-engines, and other similar motive powers.

Having described my said invention, what I claim as new, and desire to secure by Letters Patent, is—

The design for a motor base-frame as herein shown and described.

In testimony whereof I have signed my name to this specification in the presence of two subscribing witnesses.

JOHN A. SECOR.

Witnesses:

W. E. WILLSON,
M. B. SCANTLEBURY.
